UNITED STATES PATENT OFFICE.

FRANK S. WEAVER, OF EVANSVILLE, INDIANA.

DESIGN FOR A BADGE OR SIMILAR ARTICLE.

SPECIFICATION forming part of Design No. 32,867, dated June 26, 1900.

Application filed May 21, 1900. Serial No. 17,489. Term of patent 14 years.

To all whom it may concern:

Be it known that I, FRANK S. WEAVER, a citizen of the United States, residing at Evansville, in the county of Vanderburg and State of Indiana, have invented and produced a new and original Design for a Badge or Similar Article, of which the following is a specification, reference being had to the accompanying drawing, forming part hereof, which illustrates my design.

In the center of the design is the representation 1 of the world, of the conventional form, against a black or dark background 2, having the two groups of stars 3 and 4 on opposite sides of the globe or world 1 and a crescent moon 5 between said groups and above the world. Below the world is the representation 6 of a sun bursting through

dark clouds 7 and emitting the rays of light 8, which illuminate the face of the globe or 25 world and gradually become absorbed in the background 2.

Surrounding the parts of the design heretofore described is a plain band 9, having the two conventionalized buckles 10.

Having described my invention, what I claim as new, and desire to secure by Letters Patent, is—

The design for a badge, or similar article, as herein shown and described. 30

In testimony whereof I affix my name in the presence of two witnesses.

FRANK S. WEAVER.

Witnesses:

L. S. FORD,

PETER LIETHING.
